Primary Examiner — Paula Allen Greene(74) *Attorney, Agent, or Firm* — Alonzo & Associates;
Arlyn Alonzo(57) **CLAIM**

The ornamental design for a foldable headphone, as shown and described.

DESCRIPTION

FIG. 1 is a perspective view of an exemplary foldable headphone.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The foldable headphone may be used for listening to music and/or audio signals, and may include a microphone for recording or transmitting music and/or audio signals. The foldable headphone may be a wired or a wireless device.

1 Claim, 6 Drawing Sheets(56)
